US00D559387S

(12) **United States Design Patent** (10) **Patent No.:** **US D559,387 S**
(45) **Date of Patent:** **** Jan. 8, 2008**

(54) **CANNULA TUBE**

(75) Inventors: **Daniel M. Wing**, Utica, NY (US);
Deborah A. Laun, Syracuse, NY (US);
Frank J. Witkowski, Syracuse, NY
(US)

(73) Assignee: **ConMed Corporation**, Utica, NY (US)

(**) Term: **14 Years**

(21) Appl. No.: **29/180,667**

(22) Filed: **Apr. 28, 2003**

Related U.S. Application Data

(60) Division of application No. 10/264,530, filed on Oct. 4, 2002, which is a continuation-in-part of application No. 09/944,190, filed on Aug. 31, 2001, now Pat. No. 6,989,003.

(57) **CLAIM**

The ornamental design for a cannula tube, as shown and described.

DESCRIPTION

FIG. 1 is a perspective view of a cannula tube showing my new design;

FIG. 2 is a left side elevational view thereof, a right side elevational view being a mirror image thereof;

FIG. 3 is a front elevational view thereof, a rear elevational view being a mirror image thereof;

FIG. 4 is a top plan view thereof;

FIG. 5 is a bottom plan view thereof; and,

FIG. 6 is an alternative embodiment of the design shown in FIG. 1 thereof.

The broken lines in the figures are for illustrative purposes only and form no part of the claimed design.
